UNITED STATES PATENT OFFICE.

JACOB W. MOORE, OF OXFORD, ARKANSAS.

MAIL-BAG CATCHER.

1,141,817.

Specification of Letters Patent.

Patented June 1, 1915.

Application filed June 4, 1914. Serial No. 842,987.

To all whom it may concern:

Be it known that I, JACOB W. MOORE, of Oxford, in the county of Izard, and in the State of Arkansas, have invented a certain new and useful Improvement in Mail-Bag Catchers, and do hereby declare that the following is a full, clear, and exact description thereof.

My invention relates to mail bag catchers and my object is to provide a device, which, while simple, cheap and easy to operate and certain to catch the mail from fast moving trains, will cause no injury or damage thereto and will practically itself be indestructible, and to this end my invention consists in the mail bag catcher constructed substantially as hereinafter specified and claimed.

In the accompanying drawings—Figure 1 is a side elevation of a mail bag catcher embodying my invention, the full lines showing the position of parts when ready to receive the mail and the dotted lines showing the position of the moving parts when they have been moved as a result of the impact of the mail; Fig. 2 is a detail view in perspective of the rotatable support of the device; Fig. 3 is a similar view of the mail receiving basket.

My device is mounted at a convenient point alongside the track upon a leg-form base 10, having preferably a circular top or table 11, upon which is placed a turn table 12 connected to said top by a suitable pivot bolt 13, so that the mail-receiving basket 17 which is mounted upon and carried by said turn table, may, by the rotation of the latter be placed to receive mail from trains coming in either direction. The table top 11 at its diametrically opposite sides has radial slots 14 in its edge and pivoted to an upright or standard 15 on the turn table is a latch 16 adapted to be moved into and out of said slots and which when moved into one of the same locks the turn table securely against turning and thus maintains the basket in the desired position to receive the mail.

The mail-receiving basket 17 is preferably of wire of which is formed each of the four sides and the rear, or bottom thereof, the front, or upper side being open for the entrance of the mail and said front side being formed by a rectangular metal frame 18. Said frame 18 has a shank formed of parallel arms 19 which straddle a standard 20 which, at its lower end is pivoted to a

bracket 21 on the top of the turn table and the shank forming arms and said standard are held together by clips 22 placed at intervals, each of which consists of a U-shaped member and a plate through which the legs of the U-shaped member pass, the legs being threaded to receive clamping nuts.

The basket carrying standard 20 when in position to catch the mail stands vertically, and it is yieldingly held in vertical mail-receiving position by a coil spring 23, which at one end is connected to the standard 20 close to the basket and at the other end is connected to the upright 15, and at intervals other springs 24 are connected with said upright and the basket-carrying standard, said other springs being successively shorter in length so that when the basket-carrying arm is moved, as when under the impact of the mail pouch, first one spring and then another will be brought into action and thus a graduated cushioned resistance will be offered to the movement of the basket from the impact of the mail with the double advantage that neither mail nor apparatus will be injured by the coming together of the mail and the basket. Obviously, if a single spring having a strength or tension equal to that of the series of spring were used, the device would offer such initial resistance to the impact of the mail bag as might seriously damage the latter, or the apparatus and this effect I avoid by the series of springs which come into action one after another so that the shock is not a violent one and yet I finally yieldingly oppose the momentum of the mail and gradually bring it to rest by the action of the springs whose total resistance is greater than that of the spring first called into action. The bracket 21 is provided with ratchet teeth 25 adapted to be engaged by a spring-pressed dog, or pawl 26, pivoted to the basket-carrying standard, and as the pawl rides over the teeth during the rearward movement of the basket, the latter will automatically be restrained, or latched in the position to which it finally moved and thus rebound under the action of the springs is prevented, which, of course, might throw the mail out of the basket. As the basket swings downward it will be seen that it is in position, or may readily be moved to position, if it is not placed there by the action of the springs where the mail can be easily removed from the bottom and to facilitate that operation

the bottom 27 of the basket is preferably hinged, a suitable latch 28 being provided to hold it in its closed position.

It will be evident that by my invention 5 an apparatus is provided that possesses all the essential characteristics of an efficient and otherwise satisfactory mail bag catcher. The only parts liable to damage, or breakage, are the springs and they can be very 10 easily replaced when necessary.

By reason of the basket-supporting arms 19 being separate from the standard 20, and the use of such device as the clips 22 to connect them together, the basket can be adjusted vertically so that it may be at the proper level to receive the mail bag regardless of the level of the ground adjoining the track; and the basket is supported at a height sufficiently above the top of the front 20 standard 15 so that the mail bags will not strike the front standard in entering the basket.

Having thus described my invention what I claim is—

25 1. A mail bag catcher comprising a frame, a mail receptacle movably mounted on the frame so that it may move to and fro with reference to the frame, and a series of separate successively acting cushion devices attached to the frame independently of each other, and to the mail receptacle independently of each other.

30 2. A mail bag catcher comprising a frame, a mail receptacle movably mounted on the frame so that it may move to and fro with reference to the frame, and a series of separate successively acting cushioning devices attached to the frame independently of each other, and to the mail receptacle independently of each other, said devices consisting of springs of graduated length.

35 3. A mail bag catcher comprising a frame having a vertical standard, a mail bag receptacle, an arm pivoted to the frame and rising therefrom, and a series of successively 40 acting springs connected at one end to said standard and at the other end to said arm,

the points of connection of the springs with said arm being at different distances along the arm.

50

4. A mail bag catcher comprising a receptacle-carrying standard pivoted to swing on a horizontal axis, a spring normally holding it in a vertical position, other shorter springs connected with it and adapted successively to be brought into action and a stationary member to which said springs are connected.

55

5. A mail bag catcher comprising a receptacle-carrying standard pivoted to swing on a horizontal axis, a spring normally holding it in a vertical position, other shorter springs connected with it and adapted successively to be brought into action, a stationary member to which said springs are 60 connected and a locking dog pivoted to said standard.

65

6. A mail bag catcher comprising a base, a turn table mounted on the base, a mail receptacle, a movable arm mounted on said 70 turn table to which the receptacle is attached, a stationary member mounted on the turn table, cushioning means connected with the stationary member and said movable arm, and means to latch the turn table to hold the receptacle facing in either of opposite directions.

75

7. A mail bag catcher comprising a frame, having a vertically extending stationary arm on the forward side of the frame, a mail 80 receptacle situated above said stationary arm and in rear thereof, an arm pivoted to the frame and rising therefrom, an adjustable connection between the arm and the receptacle permitting vertical adjustment of 85 the position of the receptacle, and cushioning means connecting said arm and the stationary arm of the frame.

85

In testimony that I claim the foregoing I have hereunto set my hand.

JACOB W. MOORE.
